LIGHT FIXTURE

Isaac S. Brochstein, Houston, Tex.

Application May 24, 1951, Serial No. 15,302

Term of patent 14 years

(Cl. D48—23)

To all whom it may concern:

Be it known that I, Isaac S. Brochstein, a citizen of the United States of America, residing at Houston, Harris County, State of Texas, have invented a new, original, and ornamental Design for a Light Fixture, of which the following is a specification, reference being made to the accompanying drawing, forming a part hereof.

Fig. 1 is a bottom plan view of a light fixture showing my new design;

Fig. 2 is a top plan view thereof;

Fig. 3 is a side elevational view, the opposite side being identical; and

Fig. 4 is an end elevational view, the opposite end being identical.

I claim:

The ornamental design of a light fixture, substantially as shown and described.

ISAAC S. BROCHSTEIN.
